[57] CLAIM

The ornamental design for a birdfeeder, as shown and described.

DESCRIPTION

FIG. 1 is a perspective view of a birdfeeder showing our new design;

FIG. 2 is an elevational view taken from one side thereof, the other sides being the same as the side shown;

FIG. 3 is a top plan view thereof; and,

FIG. 4 is a bottom plan view thereof.

It is to be understood that the roof pattern is continuous throughout the area indicated in FIGS. 1, 2 and 3.

FIG-1-

FIG-2-
